CARD SHUFFLING AND DEALING DEVICE

Clifford P. Sivertson, Washington, D. C.

Application December 1, 1950, Serial No. 198,683

4 Claims. (Cl. 273—149)

1

This invention relates to card shuffling and dealing devices and more particularly to a power operated device for automatically shuffling a deck of playing cards and dealing the cards out into a predetermined number of hands with a predetermined number of cards in each hand.

It is among the objects of the invention to provide a power operated card shuffling and dealing device which provides a thorough shuffling of a deck of cards by first moving cards alternately from two separate stacks to a third stack and then distributing the cards one at a time from the third stack into a predetermined number of hands; which will move all of the cards in the two separate stacks to the third stack regardless of uneven distribution of cards in the two stacks; which will automatically discontinue distribution of the cards when a predetermined number of cards have been dealt to each hand; which will not mark or damage the cards and will not become jammed by the cards sticking together or turning in the device; which is quiet and without objectionable vibration in operation yet will shuffle and deal a deck of cards more rapidly than the cards can be shuffled and dealt by hand; which positions the hands for convenient removal by the players; and which is simple and durable in construction, economical to manufacture and operate, requires no fine adjustments, and is positive and effective in operation.

Other objects and advantages will become apparent from a consideration of the following description and the appended claims in conjunction with the accompanying drawings wherein:

Figure 1 is a top plan view of a card shuffling and dealing device illustrative of the invention;

Figure 2 is a side elevational view of the device illustrated in Figure 1;

Figure 3 is a cross sectional view on the line 3—3 of Figure 1;

Figure 4 is a fragmentary cross sectional view on the line 4—4 of Figure 3 looking in the direction of the arrows;

Figure 5 is a fragmentary cross sectional view on the line 5—5 of Figure 3;

Figure 6 is a fragmentary cross sectional view on the line 6—6 of Figure 3;

Figure 7 is a fragmentary cross sectional view on the line 7—7 of Figure 2;

Figure 8 is a fragmentary cross sectional view on the line 8—8 of Figure 2 looking in the direction of the arrows;

Figure 9 is a fragmentary cross sectional view on the line 9—9 of Figure 3; and

2

Figure 10 is a fragmentary cross sectional view on the line 10—10 of Figure 3.

With continued reference to the drawings, the card shuffling and dealing device comprises, in general, a support 10 in the form of a hollow housing, a shaft 11 journaled in the housing, a table 12 secured at its center to the upper end of the shaft 11 for rotation on the housing, a power actuated device 13, such as an electric motor, mounted in the housing 10 and drivingly connected to the shaft 11 for rotating the table 12, a motor controlling switch 14 mounted on the housing 10, a structure 15 supported on the support or housing 10 above the table 12 by the brackets 16 and 17 and including a center compartment 18 and end compartments 19 and 20, double acting card picking means 21 mounted on the structure 15 and extending longitudinally of the latter above the compartments 18, 19 and 20 for moving cards alternately and one at a time from the end compartments 19 and 20 into the center compartment 18, means 22 drivingly connecting the table 12 to the card picking means 21 for imparting reciprocating movement to the latter, a single acting card picking means 23 mounted on the structure 15 above the center compartment 18 substantially at the mid-length location of the structure and substantially perpendicular to the card picking means 21 for moving cards away from the center compartment 18, pockets 24, 25, 26 and 27 carried by the table and angularly spaced therearound for successively receiving cards from the single acting card picking means 23, means 28 connected to the single acting card picking means 23 and actuated by the pockets 24 to 27 inclusive for imparting reciprocating movement to the single acting card picking means in timed relationship to the rotation of the pockets, means 30 responsive to the presence of cards in the end pockets to maintain the double acting card picking means in operation as long as there are one or more cards in the end pockets and to discontinue operation of this double acting card picking means as soon as all of the cards have been moved from the end pockets to the center pocket, means 31 connected between means 30 and means 28 operative to maintain the single acting card picking means out of operation as long as the double acting means is operating and to initiate operation of the single acting means upon termination of the operation of the double acting card picking means, and means 32 responsive to operation of the single acting card picking means 23 to discontinue operation of this single acting means

when a predetermined number of cards have been moved from the center compartment 18 into each of the pockets 24 to 27 inclusive.

The support 10 may conveniently comprise a hollow, sheet metal housing having flat and substantially parallel top and bottom ends adapting the housing to set on a substantially horizontal supporting surface, such as a table top, and support the table 12 and structure 15 substantially parallel to the table top. The small electric motor 13 mounted in the housing 10 may be conveniently connected to the table driving shaft 11 through a worm 35 connected to the motor shaft through a speed reducing gear unit 36, and a worm gear 37 mounted on the lower end of the shaft 11. The table 12 may comprise a sheet metal plate disposed immediately above the top wall of the housing 10 and secured to the upper end of the shaft 11, a suitable bearing 38 surrounding the shaft 11 between the table and the top wall of the housing. The table is in the shape of a square having rounded corners and the pockets 24, 25, 26 and 27 extend one along each of the four straight edges of the table. Each of these pockets comprises a rectangular box having end walls, as indicated at 39 and 40 for the pocket 24, a front wall 41 pivotally connected at its two upper corners to the front or outer upper corners of the corresponding end walls and a bottom wall 42 inclined outwardly and downwardly from the top edges of the end walls at the inner ends of the latter to the bottom edge of the front wall. The front wall 41 is resiliently retained in closing position between the outer edges of the end walls and the front edge of the bottom wall by a suitable spring 43 connected to the front wall and the end wall 44 at the pivotal connection between the front wall and this end wall and the front and bottom walls are provided intermediate their length with recesses, as indicated at 44 and 45 for the pocket 27, as shown in Figure 2, so that the fingers and thumb of a player can be inserted through these recesses to grasp a stack or hand of cards in the corresponding pocket and remove the cards from the pocket by pulling the front wall of the pocket outwardly against the force of the corresponding springs, such as the spring 43.

In the arrangement illustrated, the end walls of the pockets are provided by upwardly extending projections at the rounded corners of the table, each projection providing end walls for two adjacent pockets, the end walls provided by each projection being disposed substantially at right angles to each other, as is clearly illustrated in Figure 1.

The structure 15 is of elongated, rectangular shape having a length somewhat greater than the width of the table 12 and corresponding to three times the length of a standard playing card and a width corresponding to the width of such a playing card. This structure may conveniently be formed of sheet metal and is disposed above the upper edges of the pockets 24 to 27 inclusive and substantially parallel to the table 12. The three compartments 18, 19 and 20 included in the structure 15 are each substantially of the length and width of a standard playing card, the cards being freely received therein and the center compartment 18 is disposed lower than the end compartments 19 and 20 and between the pockets 24 to 27 inclusive, the upper edge of the center compartment being

disposed slightly above the inner upper edges of the bottom walls of the pockets.

The outer ends of the end compartments 19 and 20 are left open and movable bottom plates 46 and 47 are respectively disposed in the compartments 19 and 20 substantially parallel to the bottom walls of the compartments. These plates have a width slightly less than the width of the corresponding compartments and a length greater than the length of the compartments so that the bottom plates project outwardly of the open outer ends of the compartments, as is clearly illustrated in Figures 1, 3 and 7. As illustrated in Figure 7 in connection with the compartment 20, two U-shaped springs 48 and 49 are disposed between the movable bottom wall 47 and the fixed bottom wall 50 of the compartment with their open ends fixed to the bottom wall at respectively opposite sides of the mid-length location of the latter and their legs crossing over between the fixed and movable walls of the compartment. Rollers 51 and 52 are mounted on the bight portions of the springs 48 and 49 respectively and bear against the under side of the movable bottom wall 47 near the respectively opposite ends of the latter so that the springs resiliently urge the movable bottom wall 47 away from the fixed bottom wall 50 of the compartment. Rods, as indicated at 53, are secured to the movable bottom wall 47 near the inner end of the latter and depend perpendicularly from this bottom wall through apertures in the fixed bottom wall 50 to guide the movable bottom in its movement toward and away from the fixed bottom.

Similar springs are disposed between the movable bottom wall 46 and the fixed bottom wall of the compartment 19 to resiliently urge the movable bottom 46 away from the fixed bottom of this compartment.

The center compartment 18 has a fixed bottom wall 54 and a movable bottom wall 55 disposed substantially parallel to the fixed wall 54 and movable toward and away from the latter. Tracks 56 and 57 are secured at their ends to the under surface of the movable bottom 55 of the center compartment and extend longitudinally of the movable bottom one near each side of the latter. Two levers 58 and 59 are pivotally mounted intermediate their length to the respectively opposite ends of the fixed bottom wall 54 substantially at the mid-width locations of the ends of this bottom wall and extend through openings in the end walls of the compartment 18 into the space between the movable bottom 55 and the fixed bottom 54. These levers are provided at their ends within the center compartment with sleeve formations which sleeve formations receive crossbars extending transversely of the movable bottom wall 55 and received at their opposite ends between the bottom surface of the movable bottom wall 55 and the tracks 56 and 57. Rollers, as indicated at 60 in Figure 5, are mounted on the crossbars between the corresponding levers and the tracks 56 and 57 to bear against the under side of the movable bottom wall 55. A control lever 66 extends transversely of the under side of the fixed bottom wall 54 of the center compartment adjacent the mid-length location of the fixed bottom wall and a pivot pin 67 extends through the control lever 66 adjacent the mid-length location of the latter and through the bottom wall 54 substantially at the center thereof to pivotally connect the control lever 66 to

the fixed bottom wall of the compartment. Links 68 and 69 connect the control lever 66 at respectively opposite sides of the pivot pin 67 to the ends of the lever 58 and 59 disposed outside of the center compartment. As illustrated in Figure 4, each link is provided near its ends remote from the control lever 66 with an aperture and each of the levers 58 and 59 is provided with a headed extension, as indicated at 70 in Figure 7, received in the aperture of the corresponding link.

A tension spring 71 is connected between one end of the control lever 66 and one end of the fixed bottom wall 54 of the center compartment and resiliently urges the control lever 66 in a direction to swing the portions of the levers 58 and 59 within the center compartment upwardly to raise the movable bottom wall 55 by moving the latter away from the fixed bottom wall 54. At its other end the lever 66 extends slightly beyond the side of the center compartment and is provided with a reduced extension 72 for a purpose to be presently described.

Brackets 73 and 74 are secured at their lower ends to the end compartments 19 and 20 respectively and extend upwardly from these compartments at the open, outer ends of the latter. Each of these brackets is provided at its lower end with a flange, as indicated at 75 in Figure 7, for the bracket 74, which flanges extend inwardly of the outer open ends of the end compartments 19 and 20 and overlie the movable bottom walls 46 and 47.

With this arrangement, a deck of cards can be divided into two substantially equal parts or stacks, the end of one stack may be placed on the outwardly projecting portion of the movable bottom wall 46, the end of the other stack placed on the outwardly projecting end portion of the movable bottom wall 47, and the movable bottom walls 46 and 47 then forced downwardly so that the stacks of cards can be slid under the bracket flanges and into the end compartments 19 and 20. When the pressure on the movable bottom walls 46 and 47 is released, the springs under these movable bottom walls will force the bottom walls upwardly, slightly compressing the stacks of cards between the movable bottom walls and the corresponding bracket flanges. This operation will load the device for shuffling and dealing a deck of cards.

A bar 76 of elongated, rectangular cross sectional shape is disposed between the brackets 73 and 74 at the upper ends of the latter and is connected at its respectively opposite ends to these brackets. This bar has its major faces substantially vertically disposed and is spaced above the mid-width locations of the three compartments 18, 19 and 20. Slides 77 and 78 are mounted on the bar 76 at respectively opposite sides of the mid-length location of the bar and these slides depend below the bar and are movable both longitudinally and transversely relative to the latter. Stops 79 and 80 on the upper edge of the bar near the respectively opposite ends thereof limit movement of the slides 77 and 78 respectively toward the corresponding ends of the bar. A rubber suction cup 81 is secured on the lower end of the slide 77 and a similar rubber suction cup 82 is secured on the lower end of the slide 78. The bar 76 is provided at respectively opposite sides of its mid-length location with longitudinally extending slots 83 and 84, the outer ends of which are curved downwardly transversely of the bar, as indicated at 85 for the slot 84. Pins 86 and

87 extend through the slides 77 and 78 respectively and through the corresponding slots 83 and 84 so that, when either slide is moved inwardly away from the adjacent end of the bar it is raised upwardly by the downwardly curved outer end portion of the slot and will then travel substantially horizontally to the inner end of the slot and, upon being returned to its outer position, will be moved downwardly as the corresponding pin travels through the downwardly curved outer end portion of the corresponding slot.

The two slides are connected together by a movable bar 88 which extends along the fixed bar 76 and is pivotally connected at its respectively opposite ends to the slides 77 and 78.

If the two slides 77 and 78 and the bar 88 be now reciprocated longitudinally of the fixed bar 76, starting from the position illustrated in Figure 3, the suction cup 81 will be moved downwardly into contact with the top card in the end compartment 19 and, upon movement of the slides and connecting bar toward the other end of the fixed bar 76, will move this top card from the end compartment 19 to a position immediately above the center compartment 18. Similarly, when the slide 78 is moved to the adjacent end of the fixed bar 76, the suction cup 82 will be moved downwardly into contact with the top card in the end compartment 20 and, upon movement of the slides and connecting bar in the opposite direction, will pick up this top card and move it to a position immediately above the center compartment 18.

A release pin 89 is slidably mounted in a bracket 90 carried by the slide 77 near the lower end thereof and this release pin extends through a small aperture in the suction cup and has its lower end substantially at the lower end of the suction cup 81. At its upper end the release pin has a downwardly inclined portion 91 and a compression spring 92 surrounding the release pin between the collar 90 and the end portion 91 resiliently urges the release pin upwardly to a position limited by engagement with the stop washer 93 with the under side of the collar 90 in which its lower end is substantially out of contact with the suction cup 81. A triangular cam 94 is mounted on the bar 76 near the inner end of the slot 83 and when the slide 77 approaches the inner end of the slot 83 the end portion 91 of the release pin strikes the cam 94 which forces the pin downwardly against a card carried by the suction cup 81 and causes the suction cup to release the card which it has carried to a position immediately above the center compartment 18.

The slide 78 is equipped with a similar release pin 95 slidably mounted in a collar 96 supported on the slide 78 near the lower end thereof and having a downwardly inclined upper end portion 97 engageable with a triangular cam 98 mounted on the bar 76 near the inner end of the slot 84. A spring 99 surrounding the release pin 95 between the collar 96 and the end portion 97 resiliently urges the release pin upwardly to a position determined by contact of the stop washer 100 secured on the pin near the lower end thereof with the under side of the collar 96.

With this arrangement, as the slides 77 and 78 and the bar 88 are reciprocated longitudinally of the fixed bar 76 cards will be alternately picked, one at a time, from the end compartments 19 and 20 and delivered into the center compartment 18.

The means 30 for imparting the reciprocating

movement to the double acting card picking means including the slides 77 and 78, the suction cups 81 and 82 and the connecting bar 88, includes a shaft 101 disposed substantially perpendicular to the structure 15 and journaled in a bearing 102 secured on one side wall of the center compartment 18 near one end of the center compartment. A gear 103 is secured on the lower end of this shaft and four gear sectors 104, 105, 106 and 107 are mounted on the table 12 at substantially equal angular intervals around the table supporting shaft 11. The two gear sectors 105 and 107 have their gear teeth on their inner sides facing the shaft 11 and the two oppositely disposed gear sectors 104 and 106 have their gear teeth on their outer sides remote from the shaft 11. These gear sectors are spaced outwardly from the shaft 11 so that the teeth of the sectors 105 and 107 will engage the teeth of gear 103 at the outer side of the gear and the teeth of gear sectors 104 and 106 will mesh with the teeth of the gear 103 at the inner side of the gear as the table rotates. These reverse gear sectors will impart rotational movement to the gear 103 and the shaft 101 in alternately opposite directions as the table rotates past the gear 103 and will impart four rotational movements to the gear 103 for each rotation of the table.

A rod like arm 108 is pivotally connected at one end to the shaft 101 near the upper end of the latter against rotational movement of the shaft relative to the arm and a tubular arm or sleeve 109 receives the arm 108 at the end of the latter remote from the shaft 101 and the tubular arm 109 is pivotally connected at its other end to the slide 77 by a bracket 110 secured to the slide by a link 111 which is apertured to receive the pin 86 and to receive a pin 112 extending through the bracket, the link 111 and the slot 83 in the bar 76.

With this arrangement, when the table 12 rotates, imparting periodic rotational movements in opposite directions to the shaft 101, the double acting card picker will be reciprocated longitudinally of the bar 76 to move cards alternately and one at a time from the end compartments 19 and 20 into the center compartment 18.

While the cards are being moved from the end compartments into the center compartment the movable bottom wall 55 of the center compartment is held down against the fixed bottom wall 54 against the force of spring 71. This is accomplished by a manually operated lever 113 pivotally mounted intermediate its length by a pivot pin 114 on the side wall of the center compartment at the side of the latter from which the reduced end 72 of the control lever 66 projects. At its lower end this lever 113 is pivotally connected to the reduced end portion 72 of the control lever 66 by a slotted link 115 so that, when the lever 113 is in one position the control lever 66 is held in a position to maintain the movable bottom wall 55 adjacent the fixed bottom wall 54 and when the lever 113 is in a different operative position, the control lever 66 is moved to free the spring 71 to resiliently urge the movable bottom wall 55 upwardly away from the fixed bottom wall 54.

An arm 116 is pivotally connected at one end to the hand lever 113 immediately above the pivot pin 114 and bears at its upper edge against a fixed slide block 117 mounted on the adjacent side wall of the center compartment 18. A spring 118 acting between the lever 113 and the arm 116 resiliently maintains the arm in contact with the

slide block. A plunger 119 is vertically disposed adjacent the side wall of the center compartment and slidably mounted in a bracket 120 carried by the center compartment side wall. The plunger 119 is of elongated, rectangular cross sectional shape and is provided with an outwardly extending shoulder near its lower end. The arm 116 is provided near its distal end with stepped recesses, as clearly illustrated in Figure 10 and, when the hand lever 113 is moved to a position to hold the movable bottom wall 55 of the center compartment down, the arm 116 is moved so that the larger recess at the distal end thereof registers with the adjacent end of the plunger 119 permitting the plunger to drop. A link 121 is pivotally connected at one end to the plunger 119 near the upper end of the latter and at its other end to the adjacent side wall of the end compartment 19. Intermediate its length this link is in engagement at its upper edge with an annular collar 122 on the shaft 101. When the plunger 119 is permitted to drop, the link 121 moves down permitting the shaft 101 to descend and bring the gear 103 into engagement with the sector gears 104 to 107 inclusive, thereby placing the double acting card picking means 21 in operation.

A lever 123 is pivotally mounted intermediate its length on the side of the end compartment 19 adjacent the outer end of the latter and has at its upper end an offset portion extending over the adjacent portion of the compartment 19. A similar lever 124 is pivotally mounted intermediate its length on the side of the end compartment 20 near the outer end of the latter and has at its upper end an offset portion overlying the adjacent portion of the compartment 20. An elongated link 125 is pivotally connected at its respectively opposite ends to the levers 123 and 124 by lost motion connections and underlies intermediate its length a lateral shoulder 126 on the plunger 119.

A looped spring 127 is mounted in the end compartment 119 at the outer corner thereof adjacent the lever 123 and has one leg in registry with a slot in the movable bottom wall 46 of this end compartment. A similar looped spring 128 is secured to the under side of the movable bottom wall 47 of the end compartment 20 and has one leg in registry with a slot in the bottom wall 47. When the last card in either of the end compartments is withdrawn the corresponding spring 127 or 128 will move through the slot in the corresponding movable bottom wall and strike the offset portion of the corresponding lever 123 or 124 to turn the lever about its pivotal connection with the associated end compartment.

Assuming that one end compartment is emptied before the other, when the associated lever 123 or 124 is turned in the above indicated manner, it will raise the link 125 until the link is brought into firm engagement with the shoulder 126 on the plunger 119 but will not raise the plunger to any material extent. When the last card is now removed from the other compartment and the corresponding lever is turned by the associated spring, the corresponding end of the link 125 will also be raised, further raising the intermediate portion of the link and lifting the plunger 119. Lifting of the plunger 119 raises the link 121, as explained above, which link acting against the collar 122, will raise the shaft 101 and bring the gear 103 out of mesh with the gear sectors 104 to 107 inclusive. This will discontinue the operation of the double act-

ing card picking means when the last card has been removed from the end compartments 19 and 20.

The single acting card picking means now comes into operation to move the cards one by one from the center compartment 18 into the pockets 24 to 27 inclusive carried by the table 21.

The single acting card picking means comprises a bar 130 of elongated, rectangular cross sectional shape secured at one end to the bar 76 and extending perpendicularly from the mid-length location of the latter with its major faces substantially vertically disposed. The distal end of the bar 130 is disposed above the pockets 25 to 27 inclusive, as the pockets rotate past this bar, and a slide 131 is slidably mounted on the bar 130 and depends therebelow. A rubber suction cup 132 is mounted on the lower end of the slide 131 and the bar 130 is provided with a longitudinally extending slot 133 having a downwardly curved portion 134 at its inner end. A pin 135 extends through the slide 131 and the slot 133. A card releasing pin 136 is slidably carried by the slide 131 and extends through an aperture in the cup 132 and this pin is actuated by a triangular cam, similar to the cams 94 and 98, disposed near the distal or outer end of the bar 130 to force the pin downwardly and release a card from the cup 132 when the slide 131 is moved to the outer end of the slot 133. When the slide 131 is moved to the inner end of the slot it is moved downwardly by the downwardly curved slot portion 134 and brought into engagement with the top card in the center compartment 18. Reciprocation of the slide 131 longitudinally of the bar 130 will thus move cards one by one from the center compartment 18 and drop them into the pockets 24 to 27 inclusive as the pockets move past the outer end of the bar 130.

The mechanism for imparting reciprocating movement to the slide 131 comprises a bell crank lever 137 journaled in an elongated bearing 138 mounted on the side of the end compartment 20. The distal end of the crank at one end of the bell crank lever 137 is pivotally connected by an elongated link 139 to the slide 131 and the crank at the other end of the bell crank lever depends into the path of the end walls of the pockets 24 to 27 inclusive so that, as the table rotates with these pockets, rotational movements will be periodically imparted to the bell crank lever which movements will be converted by the link 137 into reciprocating movements of the slide 131.

Contact of the pocket end walls with the end of the bell crank will move the slide 131 inwardly. Movement of the slide outwardly is resiliently compelled by a spring 140 acting between the side wall of the end compartment 20 and the crank on the corresponding end of the bell crank 137 at the end of bearing 138 remote from bar 130.

An angle bracket 141 is mounted on the bar 76 opposite the adjacent end of the bar 130 and projects outwardly over the end of the bell crank 137 connected to the link 139. A latch dog 142 pivotally mounted on the outer end of the angle bracket 141 engages the distal end of the crank connected to link 139 and holds the bell crank in position such that the crank at the other end thereof is out of contact with the end walls of the pockets. Under these conditions the

single acting card picking means is held out of operation.

A rectangular abutment 143 is hingedly mounted at one edge to the upper edge of the side wall of the center compartment on which the plunger 119 is mounted and is spring urged to a position in which it is disposed entirely outside of the interior of the center compartment.

When the plunger 119 is moved upwardly upon emptying of both of the end compartments 19 and 20, as explained above, its upper end engages the rectangular abutment 143 and moves this abutment to a position in which it extends inwardly of the top edge of the center compartment. At the same time, the lower end of the plunger disengages from the arm 116 permitting the manually operated lever 113 to swing and free the spring 71 for raising the movable bottom of the center compartment upwardly away from the fixed bottom wall of this compartment. The cards in the center compartment are then slightly compressed between the movable bottom wall 55 and the abutment 143 and held in position to be picked up by the suction cup 132 of the single acting card picking means. At the same time, the plunger 119 raises a hook 144, one end of which is connected to the plunger 119 at the upper end of the latter, and the other end of which is connected to the latch dog 142 near the distal end of the latter. Raising of the hook 144 lifts the latch dog 142 to free the bell crank 137 thereby initiating operation of the single acting card picking means when the operation of the double acting card picking means is terminated by removal of all of the cards from the end compartments 19 and 20.

As the single acting card picking means is actuated by the end walls of the pockets as they rotate with the table 12, the operation of this single acting card picking means will be timed relative to the rotational movements of the pockets so that a card will be deposited in each pocket by this single acting means as the pockets move successively past the distal end of the bar 130.

The card shuffling and dealing device thus thoroughly intermixes the cards contained in the two stacks originally placed in the end compartments 19 and 20 and then reshuffles these cards as it deals by placing only the fourth card dealt in any particular one of the card receiving pockets.

As the single acting card picking means 23 operates to deal the cards from the center stack successively into the card receiving pockets, the means 29 for predetermined the number of cards dealt into each of the pockets comes into operation.

This means 29 comprises a small wheel 145 journaled at its center on one side of the bar 130 at the distal end of the latter and having an annular series of ratchet teeth 146 on the face thereof remote from the bar 130. A light, resilient lever 147 is pivotally mounted intermediate its length on the bar 130 below the wheel 145 and has one end in engagement with the ratchet teeth 146. The other end of the lever is curved upwardly, as indicated at 148, and is disposed below the suction cup 132 when the latter is at its limiting position adjacent the distal end of the bar 130, as is particularly illustrated in Figure 5.

With this arrangement, when a card is moved outwardly by the suction cup 132 it strikes the lower end of the lever 147 moving this lever about its pivotal connection with the bar 130 so that the upper end of the lever will step back one ratchet

tooth 146. The card strikes the lever before the slide 131 reaches the outer end of slot 133 and further movement of the slide causes the slide to engage the lever 147 near its upper end and rotate the wheel 145 a distance corresponding to the angular space occupied by a ratchet tooth 146. Step by step movement is thus imparted to the wheel 145 as the slide 131 is reciprocated back and forth longitudinally of the bar 130.

A slide rod 149 is slidably mounted on the bar 130 near the upper end of the latter by the bearings 150 and 151 and has a pointed detent 152 projecting downwardly therefrom and terminating near the axle 153 of the wheel 145. Pins 154 and 155 project from the face of the wheel 145 from which the ratchet teeth 146 extend at diametrically opposed positions on the wheel and are successively engageable with the detent 152 of the slide rod 149 to force this slide rod longitudinally in a direction away from the wheel axle 153.

There are preferably eight ratchet teeth on the wheel and two pins so that the slide rod 149 will be given a longitudinal movement each time four cards are dealt by the single acting card picking means.

A disc 156 is journaled at its center on the angle bracket 141 immediately above the bottom leg of the angle bracket which carries the latch dog 142. This disc has an annular series of ratchet teeth 160 on one face thereof and has an annular series of angularly spaced apart, screw threaded holes 161 disposed immediately within the series of ratchet teeth. These holes are consecutively numbered to indicate the number of cards that will be dealt in each hand by the device before a particular hole reaches a predetermined position as the disc is rotated.

A lever 162 is pivotally mounted intermediate its length on the bar 130 near the proximal end of the latter and the adjacent ends of the lever 152 and the slide rod 149 are pivotally interconnected by a link 163. The link 163 is disposed at an angle to the slide rod 149 so that, as the slide rod reciprocates, the lever will be swung about its pivotal connection with the bar 130. The other end of the lever 162 is in engagement with the ratchet teeth 160 on the disc 156 and swinging over the lever will impart step by step rotational movement to the disc. At its opposite side the disc is provided with an annular groove 164 within which is an annular series of angularly spaced apart depressions 165. A spring latch 166 mounted at one end on the angle bracket has at its other end a detent engaging in the notches 165 to hold the disc against return rotational movement.

A clock spring 167 surrounds the disc axle 168 and is secured at one end to the latter. The other end of the spring is secured to the disc adjacent the groove 164, as indicated at 169, and urges the disc to rotate in a direction opposite that in which it is rotated by the lever 162 engaging the ratchet teeth 160.

A pin 170 is threaded into a selected one of the holes 161 and is engageable in a predetermined rotational position of the disc with an upwardly projecting arm of a trigger 171 slidably mounted on the angle bracket 141 at the lower side of the disc. A shaft 172 is journaled on the angle bracket 141 and carries near one end a cam 173 disposed between the lever 162 and the spring latch 166. The lever 162 is also resilient, being provided as a flat spring, and when the cam 173 is rotated it forces the spring latch arm 166 and

the lever 162 away from the disc to free the disc for rotation by the clock spring 167.

An arm 174 is secured to the end of the shaft 172 remote from the cam 173 and this arm is pivotally connected at its end remote from the shaft 172 to the end of the slide 171 remote from the upwardly projecting tongue 175.

With this arrangement, when the pin 170 strikes the tongue 175 and moves the slide 171, the cam 173 is turned to release the disc 156 which is then turned by the spring 167 back to its neutral position, as illustrated in Figure 5, suitable stop means being provided for stopping the disc in this neutral position.

As the disc 156 is advanced one hole 161 each time a card is dealt in each of the card receiving pockets, the pin 170 will contact the tongue of the slide 171 when a predetermined number of cards has been dealt into each pocket depending on the hole selected for the pin.

A small bell crank 176 is mounted intermediate its length on the angle bracket 141 and has one end disposed adjacent the distal end of the slide tongue 175 so that this end of the bell crank 25 will be contacted by the pin 170 when the pin reaches the tongue of the slide. The other end of the bell crank 176 engages an extension 177 provided on the adjacent end of the latch dog 142 to swing the latch dog down into engagement with the adjacent end of the bell crank 137 and thereby terminate operation of the single acting card picking means.

As the termination of the operation of the single acting card picking means discontinues 35 the dealing of cards into the card receiving pockets, the number of cards dealt into each pocket will be predetermined by the setting of the pin 170 relative to the disc 156.

The device is conditioned for a subsequent 40 shuffling and dealing operation by first inserting the two parts of a deck of cards into the end compartments 19 and 20 and then moving the lever 113 to permit the plunger 119 to drop and to hold the movable bottom wall of the center compartment down. Dropping of the plunger 119 will permit the gear 103 to re-engage the gear sectors 104 to 107 inclusive whereupon, if the table is being rotated by the motor 113, operation of the double acting card picking means 45 will begin and the shuffling and dealing operation of the device will be automatically carried out in the manner particularly pointed out above.

The invention may be embodied in other specific forms without departing from the spirit or essential characteristics thereof. The present embodiment is, therefore, to be considered in all respects as illustrative and not restrictive, the scope of the invention being indicated by the 55 appended claims rather than by the foregoing description, and all changes which come within the meaning and range of equivalency of the claims 60 are, therefore, intended to be embraced therein.

What is claimed is:

1. A card shuffling and dealing device comprising a support, a table rotatably mounted on said support, power operated means carried by said support and connected to said table for rotating the latter, card receiving pockets carried by said table and angularly spaced apart therearound, a structure carried by said support above said table and providing aligned card receiving compartments including a center compartment and end compartments disposed one at each end of said center compartment, said end compart-

ments being arranged to receive parts of a deck of cards through the outer ends thereof, means in said compartments resiliently supporting cards therein for convenient removal therefrom, double acting card picking means mounted on said structure and effective upon reciprocating movement thereof to move cards alternately and one at a time from said end compartments into said center compartment, means drivingly connecting said table to said double acting card picking means for imparting reciprocating movement to the latter upon rotation of said table, single acting card picking means mounted on said structure and effective upon reciprocation thereof to move cards one at a time from said center compartment into said pockets, means connected to said single acting card picking means and actuated by said pockets to impart reciprocating movement to said single acting card picking means in timed relationship to the rotation of said pockets, means connected to said means drivingly connecting said table to said double acting card picking means and to said means connected to said single acting card picking means and responsive to the presence of cards in said end pockets to maintain said double acting card picking means in operation and said single acting card picking means out of operation as long as one or more cards remain in either of said end pockets and to discontinue operation of said double acting card picking means and initiate operation of said single acting card picking means as soon as all cards have been removed from said end pockets, and adjustable means connected to the means connected to said single acting card picking means and responsive to operation of the latter to discontinue operation of said single acting card picking means when a predetermined number of cards has been moved thereby from said center compartment into each of said pockets.

2. A card shuffling and dealing device comprising a support, a table rotatably mounted on said support, power operated means carried by said support and connected to said table for rotating the latter, card receiving pockets carried by said table and angularly spaced apart therearound, a structure carried by said support above said table and providing aligned card receiving compartments including a center compartment and end compartments disposed one at each end of said center compartment, said end compartments being arranged to receive parts of a deck of cards through the outer ends thereof, means in said compartments resiliently supporting cards therein for convenient removal therefrom, double acting card picking means mounted on said structure and effective upon reciprocating movement thereof to move cards alternately and one at a time from said end compartments into said center compartment, means drivingly connecting said table to said double acting card picking means for imparting reciprocating movement to the latter upon rotation of said table, single acting card picking means mounted on said structure and effective upon reciprocation thereof to move cards one at a time from said center compartment into said pockets, means connected to said single acting card picking means and actuated by said pockets to impart reciprocating movement to said single acting card picking means in timed relationship to the rotation of said pockets, means connected to said means drivingly connecting said table to said double acting card picking means and to said means connected to said single acting card picking means and responsive to the presence of cards in said end pockets to maintain said double acting card picking means in operation and said single acting card picking means out of operation as long as one or more cards remain in either of said end pockets and to discontinue operation of said double acting card picking means and initiate operation of said single acting card picking means as soon as all cards have been removed from said end pockets, and adjustable means connected to the means connected to said single acting card picking means and re-

acting card picking means and to said means connected to said single acting card picking means and responsive to the presence of cards in said end pockets to maintain said double acting card picking means in operation and said single acting card picking means out of operation as long as one or more cards remain in either of said end pockets and to discontinue operation of said double acting card picking means and initiate operation of said single acting card picking means as soon as all cards have been removed from said end pockets, adjustable means connected to the means connected to said single acting card picking means and responsive to operation of the latter to discontinue operation of said single acting card picking means when a predetermined number of cards has been moved thereby from said center compartment into each of said pockets, manually operated means connected to said power operated means for controlling the operation of the latter, and manually operated means connected to the means imparting reciprocating movement to said card picking means for resetting the motion imparting means to place said double acting card picking means in operation and said single acting card picking means out of operation for a subsequent card reshuffling and dealing operation of the device.

3. A card shuffling and dealing device comprising a support, a table rotatably mounted on said support, power operated means carried by said support and connected to said table for rotating the latter, card receiving pockets carried by said table and angularly spaced apart therearound, a structure carried by said support above said table and providing aligned card receiving compartments including a center compartment and end compartments disposed one at each end of said center compartment, said end compartments being arranged to receive parts of a deck of cards through the outer ends thereof, means in said compartments resiliently supporting cards therein for convenient removal therefrom, double acting card picking means mounted on said structure and effective upon reciprocating movement thereof to move cards alternately and one at a time from said end compartments into said center compartment, means drivingly connecting said table to said double acting card picking means for imparting reciprocating movement to the latter upon rotation of said table, single acting card picking means mounted on said structure and effective upon reciprocation thereof to move cards one at a time from said center compartment into said pockets, means connected to said single acting card picking means and actuated by said pockets to impart reciprocating movement to said single acting card picking means in timed relationship to the rotation of said pockets, means connected to said means drivingly connecting said table to said double acting card picking means and to said means connected to said single acting card picking means and responsive to the presence of cards in said end pockets to maintain said double acting card picking means in operation and said single acting card picking means out of operation as long as one or more cards remain in either of said end pockets and to discontinue operation of said double acting card picking means and initiate operation of said single acting card picking means as soon as all cards have been removed from said end pockets, and adjustable means connected to the means connected to said single acting card picking means and re-

sponsive to operation of the latter to discontinue operation of said single acting card picking means when a predetermined number of cards has been moved thereby from said center compartment into each of said pockets, said double acting card picking means comprising a bar disposed above and substantially parallel to said structure and having longitudinally extending slots therein disposed one at each side of the mid-length location thereof, slides mounted on said bar and slideable one along each of said slots, each of said slots having a downwardly turned portion at its end adjacent the corresponding end of said bar and each of said slides depending below said bar and having a pin extending through the corresponding slot, suction cups mounted one on each slide at the lower end of the latter, card releasing pins slidably mounted one on each slide and extending through the associated suction cup, and cams mounted on said bar and engaging said card releasing pins at predetermined positions of said slide along said bar.

4. A card shuffling and dealing device comprising a support, a table rotatably mounted on said support, power operated means carried by said support and connected to said table for rotating the latter, card receiving pockets carried by said table and angularly spaced apart therearound, a structure carried by said support above said table and providing aligned card receiving compartments including a center compartment and end compartments disposed one at each end of said center compartment, said end compartments being arranged to receive parts of a deck of cards through the outer ends thereof, means in said compartments resiliently supporting cards therein for convenient removal therefrom, double acting card picking means mounted on said structure and effective upon reciprocating movement thereof to move cards alternately and one at a time from said end compartments into said center compartment, means drivingly connecting said table to said double acting card picking means for imparting reciprocating movement to the latter upon rotation of said table, single acting card picking means mounted on said structure and effective upon reciprocation thereof to move cards one at a time from said center compartment into said pockets, means connected to said single acting card picking means and actuated by said pockets to impart reciprocating movement to said single acting card picking means in timed relationship to the rotation of said pockets, means connected to said means drivingly connecting said table to said double acting card picking means and to said means connected to said single acting card picking means and responsive to the presence of cards in said end pockets to maintain said double acting card picking means in operation and said single acting card picking means out of operation as long as one or more cards re-

main in either of said end pockets and to discontinue operation of said double acting card picking means and initiate operation of said single acting card picking means as soon as all cards have been removed from said end pockets, and adjustable means connected to the means connected to said single acting card picking means and responsive to operation of the latter to discontinue operation of said single acting card picking means when a predetermined number of cards has been moved thereby from said center compartment into each of said pockets, said double acting card picking means comprising a bar disposed above and substantially parallel to said structure and having longitudinally extending slots therein disposed one at each side of the mid-length location thereof, slides mounted on said bar and slideable one along each of said slots, each of said slots having a downwardly turned portion at its end adjacent the corresponding end of said bar and each of said slides depending below said bar and having a pin extending through the corresponding slot, suction cups mounted one on each slide at the lower end of the latter, card releasing pins slidably mounted one on each slide and extending through the associated suction cup, and cams mounted on said bar and engaging said card releasing pins at predetermined positions of said slide along said bar, and said single acting card picking means comprising a bar secured at one end to the bar of said double acting card picking means and extending perpendicularly from the latter at the mid-length location thereof, the bar of said single acting means having a slot extending longitudinally thereof and provided with a downwardly turned end portion adjacent the bar of said double acting means, a slide mounted on the bar of said single acting means for reciprocation along the corresponding slot and depending below such bar, a suction cup mounted on the lower end of the last mentioned slide, and a card releasing pin slidably mounted on said last mentioned slide and extending through the last mentioned suction cup, and a cam carried by the bar of said single acting means at the outer end of said bar for engaging said card releasing pin and moving the latter to release a card from the associated suction cup.

CLIFFORD P. SIVERTSON.
